UNITED STATES PATENT OFFICE

DONALD R. DOHNER, OF PITTSBURGH, PENNSYLVANIA, ASSIGNOR TO WESTINGHOUSE ELECTRIC & MANUFACTURING COMPANY, A CORPORATION OF PENNSYLVANIA

DESIGN FOR A REFRIGERATOR CABINET OR SIMILAR ARTICLE

Application filed February 12, 1932. Serial No. 42,838. Term of patent 7 years.

To all whom it may concern:

Be it known that I, DONALD R. DOHNER, a citizen of the United States, residing at Pittsburgh, in the county of Allegheny and State of Pennsylvania, have invented a new, original, and ornamental Design for a Refrigerator Cabinet or Similar Article, of which the following is a specification, reference being had to the accompanying drawing, forming a part thereof.

The figure is a perspective view of a refrigerator cabinet, for example, a water

cooler, showing my new and ornamental design.

The dominant feature of the design resides in the body of the refrigerator cabinet.

I claim:

The ornamental design for a refrigerator cabinet or similar article, substantially as shown and described.

In testimony whereof, I have hereunto subscribed my name this 8th day of February, 1932.

DONALD R. DOHNER.
